UNITED STATES PATENT OFFICE.

HOWARD E. COFFIN, OF DETROIT, MICHIGAN, ASSIGNOR, BY MESNE ASSIGNMENTS, TO THE DETROIT MOTOR & MACHINE COMPANY, OF DETROIT, MICHIGAN, A CORPORATION OF MICHIGAN.

ROTARY VALVE.

1,168,479.

Specification of Letters Patent.

Patented Jan. 18, 1916.

Application filed February 4, 1911. Serial No. 606,531.

To all whom it may concern:

Be it known that I, HOWARD E. COFFIN, a citizen of the United States of America, residing at Detroit, in the county of Wayne 5 and State of Michigan, have invented certain new and useful Improvements in Rotary-Valve Construction, of which the following is a specification, reference being had therein to the accompanying drawings.

10 The invention relates to rotary valves particularly designed for use in connection with explosion engines, and the invention consists in certain features of construction as herein-after set forth.

15 In the drawings, Figure 1 is a vertical central section through a portion of the engine casing showing the valve construction; Fig. 2 is a sectional perspective view thereof. Fig. 3 is a view similar to Fig. 1 showing a modified construction; Fig. 4 shows 20 still another modification.

My improved valve belongs to the disk type and is preferably arranged in the head of the engine cylinder, and is operated by 25 a rotary stem passing out through the head of the cylinder. With such a construction the lower face of the valve is exposed to the pressure developed within the cylinder in the explosion of the gases which force it outward against the valve seat and greatly increases the frictional resistance to rotation.

It is one of the objects of the present invention to reduce the friction and the wear of the seat and valve disk by providing a 35 thrust bearing which will hold these parts slightly separated.

It is a further object to provide means for adjusting this thrust bearing to vary the distance of the valve from its seat, and still another object is to provide means for yieldably drawing the disk to its seat.

In detail, A is the engine cylinder which as shown has a counterbore B at its upper end in which is placed the disk valve C, and 45 D is the head of the cylinder against which the disk is seated.

E is the rotary stem for the valve which extends outward through the bearing F in the head, preferably surrounded by a water jacket G, and at its upper end has mounted 50 thereon a gear wheel H. This gear wheel forms the driver for the valve and is operated by a suitable train of gearing (not shown) from the crank shaft of the engine.

With the construction as thus far described the pressure developed within the engine cylinder will force the disk upward against its seat, while the suction in the cylinder will tend to draw the disk away from its seat. The combined action will cause a hammering of the valve on its seat which is detrimental, while the pressure during the explosion and compression strokes of the engine increase the frictional resistance. I therefore provide a bearing I for taking the thrust of the valve which is preferably located in an enlargement I' of the bearing F for the stem. As shown, the bearing I is formed by balls I² between races I³ and I⁴, the former bearing against a shoulder J 70 upon the valve stem.

K is an adjustable seat for the ball-race I⁴ which preferably has a threaded engagement with a flange L on the casing and is arranged to surround the hub H' of the gear 75 wheel H. Thus by adjusting the member K the position of the ball-race I is shifted, which causes a corresponding adjustment of the stem E and disk C.

The gear wheel H is preferably feathered 80 as indicated at M to the rotary stem E so as to permit an independent longitudinal movement of said stem. This will allow the disk and stem to move inward, and to prevent such a result during the suction stroke 85 of the engine, a spring or other resilient yieldable means is employed for drawing the disk upward. This preferably consists of a spring washer N which is arranged to bear upon the gear wheel H and centrally 90 engages a pin O in the valve stem. The arrangement is such that the spring is normally under slight tension and will act to draw the valve to its seat but will yield to prevent any binding.

With the construction as described, in use the valve when first positioned may be slightly spaced from its seat, or if desired may be tight against the seat so as to permit grinding of the surfaces into perfect contact. In each case the thrust bearing I will limit the longitudinal movement of the valve stem and on account of the balls and the slight radial distance from the axis will reduce the friction. Where the valve is in 105 full contact with the seat it will soon wear so as to be separated therefrom and the thrust bearing will then prevent further

wear. If at any time it is desired to relieve the valve from its seat, the member K may be adjusted to shift inward the bearing I. This movement will however, be arrested by the tension of the spring N which will prevent the valve from leaving its seat by suction. Thus the hammering of the valve against its seat and the frictional resistance of the seat to the rotation of the valve, is reduced to the minimum.

It will be noted that the inner end of the hub H' bears against the thrust bearing I so that the inward thrust due to the suction within the cylinder is taken care of by this bearing with slight frictional resistance. The construction is also one that will permit of varying the thickness of oil film between the valve and its seat so as to provide the required lubrication without danger of carbonization.

The construction shown in Fig. 3 is modified from that shown in Fig. 1 by the substitution of a pair of bearings for the single bearing I. A lower bearing P is located in the recess I' in place of the bearing I and is merely an end thrust bearing, while the upper bearing Q is above the gear wheel and located in a recess R in the cap or cover S of the engine case. This latter bearing is a journal or radial thrust bearing, and the two bearings P and Q together perform the function of the single bearing I in the construction shown in Fig. 1. This modification permits of making the bearings smaller than would be possible where both end thrust and radial thrust is to be taken care of in a single bearing.

The construction shown in Fig. 4 is a further modification in which a rigid shoulder is substituted for the resilient member N in Fig. 1. This shoulder is formed by the lock-nuts T and T' engaging a threaded portion of the stem and arranged above the gear wheel H. Thus, by adjusting the nuts T and T' sufficient clearance is provided for the valve in relation to its seat, while said nuts prevent any further movement of the valve away from the seat.

What I claim as my invention is:

- 50 1. The combination with a rotary disk valve and a seat therefor, and a thrust bearing for said valve independent of said seat for relieving the load therefrom.
- 55 2. The combination with a rotary valve and its seat, of a stem for said valve, and a thrust bearing engaging said stem for relieving the load from said seat.
- 60 3. The combination with a rotary disk valve and its seat, of a stem for said valve, and a thrust bearing surrounding said stem and engaging a shoulder thereon and adapted to relieve the load from said seat.
- 65 4. The combination with a valve and its seat, of a stem for said valve passing outward through its seat, a thrust bearing sur-

rounding said stem and engaging a shoulder thereon, and means for adjusting the position of said thrust bearing for variably relieving the load from said seat.

5. The combination with a rotary disk valve and its seat, of a stem for said valve passing outward through the seat, a bearing in which said stem is journaled, a thrust bearing engaging an enlargement in said bearing, and means for positioning said thrust bearing to adjust the valve a predetermined distance from its seat.

6. The combination with a rotary disk valve and its seat, of a stem passing outward from said valve through said seat, a shoulder on said stem, a thrust bearing engaging said shoulder, and an adjustable member for shifting the position of said thrust bearing for variably adjusting the valve from its seat.

7. The combination with a rotary disk valve and its seat, of a stem for said valve passing outward through said seat, a bearing for said stem, a drive wheel yieldably mounted on said stem beyond said bearing, and a spring between the shoulder on said stem and said drive wheel for yieldably drawing said valve to its seat.

8. The combination with a rotary disk valve and its seat, of a stem passing outward through said seat, a bearing for said stem, a drive wheel yieldably secured to said stem and having a thrust engaging with said bearing and a spring washer surrounding said stem engaging a pin therein and bearing against said drive wheel to yieldably draw said stem outward.

9. The combination with a rotary disk valve and a seat therefor, of a stem for said valve passing outward through said seat, a journal bearing for said stem, a thrust bearing engaging a shoulder on said stem and located in an enlargement in said journal bearing, a drive wheel mounted on said stem beyond said thrust bearing and longitudinally slidably on the stem, and a spring washer bearing against said drive wheel and a pin on said stem.

10. The combination with an engine cylinder and the head thereof, of a rotary disk valve seated against the head of said cylinder, a rotary stem passing outward through said head, a journal bearing engaging a shoulder on said stem and located in an enlargement of said journal bearing, a drive wheel beyond said thrust bearing and having a hub in contact therewith, an adjustable seat for said thrust bearing surrounding said hub, a spring washer bearing on said drive wheel and engaging a pin on said stem.

11. The combination with a rotary valve and its seat, of a stem for said valve, a thrust bearing engaging said stem for relieving the load from said seat, and means

for adjusting the thrust bearing to vary the distance of the valve from its seat.

12. The combination with a rotary valve and its seat, of a stem for said valve, and 5 means engaging said stem for relieving the load from said seat.

13. The combination with a rotary valve and its seat, of a stem for said valve, and

adjustable means engaging said stem for variably relieving the load from said seat. 10

In testimony whereof I affix my signature in presence of two witnesses.

HOWARD E. COFFIN.
